UNITED STATES PATENT OFFICE.

ANNA ELFRIDA McMAHON, OF ATLANTA, GEORGIA.

DESIGN FOR A SPOOL-HOLDER.

49,098.

Specification for Design.

Patented May 23, 1916.

Application filed March 10, 1916. Serial No. 83,439. Term of patent 7 years.

To all whom it may concern:

Be it known that I, ANNA ELFRIDA McMAHON, a citizen of the United States, residing at Atlanta, in the county of Fulton and State of Georgia, have invented a new, original, and ornamental Design for Spool-Holders, of which the following is a specification, reference being had to the accompanying drawing, forming a part thereof.

top plan view; and Fig. 3 is a bottom plan view of a spool holder, showing my new design.

I claim:

The ornamental design for a spool holder, as shown.

ANNA ELFRIDA McMAHON.
